P. W. JONES

BRACELET

Filed Jan. 12, 1927

UNITED STATES PATENT OFFICE.

PERCIVAL W. JONES, OF WARWICK, RHODE ISLAND, ASSIGNOR TO LOUIS STERN CO., OF PROVIDENCE, RHODE ISLAND, A CORPORATION OF RHODE ISLAND.

BRACELET.

Application filed January 12, 1927. Serial No. 180,737.

This invention relates to improvements in the construction of a flexible bracelet or chain formed of a plurality of link units hingedly connected together; and the object 5 of this invention is to provide a plurality of units, the construction of which is such that the units may be detached one from the other by a manual manipulation for the purpose of extending or shortening the operating length of the bracelet.

A further object of the invention is to provide a bracelet having an open back and a top wall having openings therethrough to form an ornamental design with a means 15 for connecting the units together and so located as not to obstruct any of the openings through the bracelet whereby the arm of the wearer or the surface on which the bracelet is mounted may be viewed through these 20 openings to contrast with the color of the metal forming the bracelet and so enhance the appearance thereof.

A further object of the invention is to provide a solderless, rivetless bracelet link unit comprising a minimum number of parts which may be detachably connected to another like link unit in a durable and strong construction.

A still further object of the invention is 30 the mounting of a skeleton frame within an outer shell of a link unit with the skeleton frames of the link units connected together and formed of a hardened metal to withstand abuse, whereas the outer shell may be 35 of a more delicate, ornamental, precious metal attached to this skeleton frame to provide a bracelet of attractive appearance.

With these and other objects in view, the invention consists of certain novel features 40 of construction, as will be more fully described, and particularly pointed out in the appended claims.

In the accompanying drawings:

Figure 1 is a perspective view of a series 45 of link units connected together with one of these units being shown as provided with openings to form a design and enhance the ornamental appearance of the bracelet.

Figure 2 is a perspective view of the outer shell of the link unit.

Figure 3 is a perspective view of the frame of the link unit.

Figure 4 is a perspective view of the frame and shell in assembled position.

Figure 5 is a sectional bottom view of 55 two of the units assembled.

Figure 6 is a sectional end view of the bracelet showing the connection between the outer shell and frame.

Figure 7 is a sectional end view through 60 the opposite end of the bracelet showing the openings through which tweezers indicated in dotted lines may be inserted to move the arms inwardly for detaching or attaching 65 the units.

Figure 8 is a perspective view of a modification with portions broken away to show its construction.

It is found in the practical construction and use of bracelets of this character, of 70 advantage to provide means whereby the different units may be disconnected from or connected to each other for readily adjusting the operating length of the bracelet to fit the wrists of the different wearers, and in 75 order to accomplish this result in a simple, practical and durable construction I have provided a link consisting of a frame and a shell embracing the frame of such construction that the frames of the different units 80 may be detachably connected together and made of material to withstand abusive treatment and the shell covering these frames may be of more precious metal to enhance the appearance of the bracelet, the frame 85 being so constructed and mounted in the shell that a pair of arms are movable at one end relative to the shell, to permit of manual manipulation for detachably connecting the units together; and the following is a 90 detailed description of one construction of bracelet and showing one means by which these advantageous results may be accomplished:—

With reference to the drawings, 10 designates an outer shell of the bracelet having a top wall 11, side walls 12 with inwardly-extending flanges 13 which house the arms 14 of the frame 16. The arms 14 are connected together by a cross-bar 15 and secured 100 adjacent one end by rolling portions 17 cut from the stock of the flanges 13 into notches 18 in the edge of the arms 14. The portions 19 of the arms 14 extend beyond the ends of the side walls 12 to form connecting ears and are pierced to provide an opening 20. These extending ear portions 19 are inserted 105 between the opposite free ends 21 of the arms

and the side walls 12 to receive a finger or projection 22 integral with and extending laterally from the free end of the arm. This finger after passing through the opening 20 extends into a recess 23 in the side wall 12 to have a bearing therein to support its end and better resist a longitudinal strain upon the different links.

In order to detach the link units, tweezers 24, a pin or the like, may be inserted through an opening 25 in the flanges to engage and move the arms 14 inwardly to the dotted line position shown in Figure 5, thus withdrawing the projections or fingers 22 from their recessed bearings 23 and the openings 20 in the ears 19 to permit detachment of the units one from the other. It will thus be seen that the frame portions 16 of the units are connected directly one to the other and as these frame portions are hidden by the shell they may be made of hardened base metal to withstand abusive treatment, whereas as the shell may be of precious metal to make the bracelet attractive and ornamental in appearance.

It will also be observed that the frame 16 is of skeleton form having a cross-bar 15 bridging between the arms 14 and is positioned about the border or ends and sides of the shell so that the openings 26 forming an ornamental design in the top wall of the shell will not be obstructed by the frame but will permit the arm of the wearer or the surface on which the bracelet is mounted to be viewed through these openings to contrast with the metal and thus by contrast set out the bracelet and the design cut therein to enhance the appearance thereof.

The fingers 22 and the arms 14 are formed by striking the metal to draw up these fingers and thus the entire frame is of one piece and as it is secured in the shell by bending the portion of the shell into engagement therewith no solder or rivets are needed in the production thereof, which is a great saving and advantage in manufacture.

The modification shown in Figure 8 has the recesses 23 extending through the side wall so that a small instrument may be inserted through the side wall to withdraw the pin from opening 20 instead of using an opening 25 in the flanges. Further, the arms 14 are offset as at 27 to align the free ends with the side walls.

The foregoing description is directed solely towards the construction illustrated, but I desire it to be understood that I reserve the privilege of resorting to all the mechanical changes to which the device is susceptible,

the invention being defined and limited only by the terms of the appended claims.

I claim:

1. A bracelet comprising a series of units connected together each unit comprising a shell having top and side walls, a pair of flexible arms separate from said shell and carried thereby, means for securing said arms in position against longitudinal movement adjacent said side walls, but permit lateral flexing of one end thereof, and formations on opposite ends of said arms consisting of projections and recesses therefor for detachably securing said units together.

2. A bracelet comprising a series of frames having resilient side arms with openings in one of their ends, fingers on the opposite ends of the arms engaging the openings in the arms of the next adjacent frame, and a shell for each frame fixedly secured to one end of each arm and leaving the other end of each arm movable relative to said shell for detachably connecting the frames together.

3. A bracelet comprising a series of units connected together, each unit comprising a shell having top and side walls, inwardly-extending flanges on said side walls, a resilient arm mounted against longitudinal bodily movement along each side wall beneath the flange thereof and extending beyond the side wall with an opening therein, a finger on the opposite free end of each arm for engaging the opening in the extending end of the arm of the next unit, the free end of said arms being movable inwardly to disengage the finger from the opening to detach the units.

4. A bracelet comprising a series of units connected together, each unit comprising a shell having top and side walls, inwardly-extending flanges on said side walls, a resilient arm mounted along each side wall beneath the flange thereof and extending beyond the end of the side wall with an opening therein, means for securing the extending ends of said arms in position, a finger on the opposite free end of each of said arms, each side wall having a recess to receive the end of a finger, each side wall flange having an opening through which said arms may be engaged to move it inwardly to receive the oppositely-extending end of the adjacent arm and permit said finger to extend through the opening therein whereby a detachable connection of the units may be obtained, and a stop lip extending from each flange to limit the inward movement of its arm.

In testimony whereof I affix my signature.

PERCIVAL W. JONES.
